UNITED STATES PATENT OFFICE.

SAMUEL GAGE, OF HOLLOWAY, LONDON, ENGLAND, ASSIGNOR TO THE LONDON GENERAL OMNIBUS COMPANY LIMITED, OF BROADWAY, WESTMINSTER, ENGLAND.

VEHICLE.

Application filed December 27, 1920. Serial No. 423,093.

To all whom it may concern:

Be it known that I, SAMUEL GAGE, subject of the King of England, residing at Holloway, London, England, have invented 5 certain new and useful Improvements in Vehicles, of which the following is a specification.

This invention is for improvements in or relating to vehicles and has for one of its 10 objects to provide a construction which shall be sufficiently rigid and strong but which at the same time shall be as light as possible.

The invention is concerned with vehicle 15 bodies whereof the framing members are mainly of wood and according to the invention a vehicle body is provided which is characterized in that the frame includes one or more metal hoops each lying vertically and in a transverse plane, each completely encircling the body of the vehicle, and each being covered and supported on their front and rear faces by wooden strips. Conveniently the metal hoops are formed 20 of plates with their breadth lying in the said transverse plane, said plates comprising roof and floor members joined to pillar members by corner gussets.

The invention is particularly applicable to 30 the construction of omnibuses, but is, of course, not limited in its application to those vehicles.

For a more complete understanding of the invention there will now be described, 35 by way of example only and with reference to the accompanying drawings, one constructional form of omnibus body according to the invention. It is to be understood, however, that the invention is not limited to the precise constructional details set forth.

In these drawings:—

Figure 1 is a perspective view from the rear of an omnibus, parts being broken 45 away for clearness;

Figure 2 is a perspective view, on a scale smaller than that of Figure 1, of a portion of the framework of the omnibus;

Figure 3 is a detail elevation of one of 50 the hoops of the framework of the omnibus showing the hoop detached and with a portion of the wooden covering for the metal removed, and

Figure 4 is a cross-section on the line 4—4 of Figure 3 but on a scale larger than 55 that of the latter.

Like reference numerals indicate like parts throughout the drawings.

The vehicle body illustrated comprises a floor 10 and an upper deck 11 which are 60 supported the one from the other mainly by four hoops 12. These hoops each comprise two upright members 13, an upper member 14 and a lower member 15 with a gusset 16 at each of the corners between 65 these members. The hoops may conveniently be roughly of rectangular shape, the corner gussets cutting off a small portion of the rectangles at each corner. As will be seen from Figure 3 the upper member 70 14 is somewhat cambered to correspond to the preferred shape of the upper deck. The hoops each stand vertically and lie in a transverse plane and they may conveniently be made of relatively thin metal 75 plates riveted together and formed with lightening holes, such as 17, if desired. Instead of a thin plate, however, any other suitable cross-section of metal may be employed according to circumstances. The 80 metal members 13, 14 and 15 of the hoops are cased in with wooden strips 18, 19 and 20 respectively, the upright members 13 and 18 preferably being arranged to form pillars 21 extending between the side windows 22 of the omnibus (see particularly 85 Figure 1). The wooden members may be secured to the metal members of the hoops by screws, bolts or rivets, or other suitable means, and if desired instead of riveting the corner gussets separately to the other 90 metal members of the hoops, they may be held in place by the screws or other means which secure the wooden strips to the metal members of the hoops. Conveniently the 95 gussets 16 project into the interior of the omnibus, and the upper gussets may be provided with covering wooden brackets 23 on which are mounted lamps 24 for illuminating the interior of the vehicle.

The hoops preferably pass across the deck of the body underneath any seats which may be placed on the top of the omnibus, and supplementary framework members may be employed to complete the structure of the 100 body. For instance in Figure 2 there is 105

illustrated a front end frame 25 and a rear end frame 26, while in Figure 1 additional strengthening members 27 are shown running under the deck of the omnibus. Standingards 28 in the interior of the omnibus may also be employed if desired.

It will be appreciated that the hoops when cased in with their wooden strips will have the same appearance as the other parts of the frame of the omnibus but will, of course, add considerably to the strength of the body. By the use of these metal reinforcements the remaining parts of the framing of the body may be made of very light construction but at the same time a body will be produced which will be equal in strength to or superior than the all-wood framing bodies heretofore constructed.

By setting the metal reinforcements edge-wise as described above a construction is provided which is particularly suitable for use in some circumstances, but it will be

appreciated that other arrangements of the reinforcements may be adopted if thought desirable.

25

What I claim as my invention and desire to secure by Letters Patent is:—

A vehicle body comprising a plurality of transversely arranged reinforcing hoops, said hoops being rigidly secured to said body so as to be incapable of independent movement, each of said hoops completely encircling said body and comprising an endless web of metal interposed between covering strips of wood and lying flatwise in the plane of the hoop, said web being composed of top and bottom and side members and corner gussets all riveted together to form a rigid member, and lamp-supporting means carried by the upper gussets of each hoop, substantially as described.

In testimony whereof I affix my signature.

SAMUEL GAGE.
